UNITED STATES PATENT OFFICE.

JOHN H. STUBBE, OF PITTSBURGH, PENNSYLVANIA.

ELEVATOR FOR AUTOMOBILE-TRUCKS AND THE LIKE.

1,390,837.

Specification of Letters Patent. Patented Sept. 13, 1921.

Application filed November 14, 1919. Serial No. 338,027.

To all whom it may concern:

Be it known that I, JOHN H. STUBBE, a citizen of the United States, residing at Pittsburgh, in the county of Allegheny and State of Pennsylvania, have invented certain new and useful Improvements in Elevators for Automobile-Trucks and the like, of which the following is a specification.

This invention relates to automobile trucks, and more particularly to a truck specially adapted for transporting and loading and unloading ice in the form of blocks or cakes.

One of the main objects of the invention is to provide a truck of this character having a vertically movable platform or elevator, constructed in such a manner as to require a relatively small head-room compared to its rise, by means of which blocks of ice may be easily raised into position adjacent the top of a refrigerator car so as to facilitate placing the ice thereon, or blocks of ice may be readily lowered from a higher level and loaded into the truck, as conditions may require. Another object is to so associate the elevator with the truck body as to enable this elevator to be positioned closely adjacent the side of a refrigerator car or other structure so as to permit the blocks of ice to be readily slid from the elevator directly onto the car roof. A further object is to provide simple and efficient means for holding the ice blocks in position upon the elevator while permitting ready loading or unloading thereof. Further objects will appear from the detailed description.

In the drawings:—

Figure 1 is a perspective side view of a truck with an elevator constructed in accordance with my invention applied.

Fig. 2 is a top plan view of the elevator and associated parts, partly broken away and in section.

Fig. 3 is a side view, partly in section, of the elevator and parts associated therewith.

Fig. 4 is a fragmentary detail top plan of the elevator frame.

Fig. 5 is a side view of the same.

Fig. 6 is a side elevation of a modification of my invention.

Fig. 7 is a top plan view of the same.

The invention is adapted particularly for use in connection with an automobile truck A having a box-like body B adapted for hauling ice in cakes or blocks. One side C of this body is shorter than the other side

and is provided, at its forward end with an end wall 1 extending a short distance across the body so as to leave, at the other side of the forward end thereof, a space or opening 2 for placing blocks of ice on or removing them from an elevator operable in the space between end wall 1 and the back wall of the cab D of the truck.

Vertically disposed cylinders 3 are secured to heavy posts 4 incorporated in the structure of the truck and positioned adjacent the end wall 1 of the body and the back of cab D, respectively. These cylinders receive pistons 4 secured on the lower ends of plungers 5 on the upper ends of which are secured caps 6 carrying forks 7 which rotatably support grooved pulleys or sheaves 8. The cylinders 4 are connected at their lower ends by a pipe 12 provided at its central portion with a T-connection 13 by means of which it may be connected to a pressure fluid supply pipe associated with a source of supply of oil or other suitable liquid from which the oil may be forced by a pump operated by the motor of the automobile into the cylinders, suitable control valves being provided for admitting the oil to or exhausting it from, the cylinders, as will be readily understood. For driving the pump, I avail myself of the means usually provided for such connections on the various makes of motor trucks, and locate the pump according to the type of body in the most convenient and simple manner.

A cable 9, having its ends secured to the upper ends of the respective cylinders by swivels 11, is passed over the sheaves and then guided freely by rollers or round corner guides 10 under the elevator designated generally by 10. By thus passing the cable 9 freely under the platform, the latter will always adjust itself in a level position, even if it should occur that one of the cylinders should rise faster than the other, due to leaking piston, unequal flow of the pressure fluid or other accidental causes.

As the elevator is supported by a two to one suspension it may be moved through twice the distance of travel of the plungers, thus producing a mechanism which is well adapted for the use intended. Also, by providing the cylinders at opposite sides of the elevator, ease and accuracy of operation are secured and possibility of binding of the parts is eliminated.

The elevator 10 is provided with a rec-

tangular base frame 14 of angle iron construction on which are secured boards 15 forming the elevator platform. Downwardly and outwardly inclined brace bars 16 are secured to this frame at their upper ends and, at their lower ends, to vertically disposed spaced angle strips 17 secured to the frame 14 substantially centrally of each end thereof. These strips receive between their outer 5 arms the central web or stem of a T-guide strip 18 the head of which is slidable in a channel member 19 secured to cylinder 3. The guide strips 18 are secured, adjacent their upper ends, to arms 20 projecting from 10 caps 6, and have their lower ends connected by cross-braces 21, so as to be held in proper operative relation to channel members 19.

It will thus be seen that the elevator platform is guided by a telescoping or differential guide construction, which will require 20 for the pistons and guides, when in its lowered position, an overhead room or clearance above the floor of the truck of approximately one half the rise of the elevator-platform only. This is obviously a very important advantage, especially when it is desired to have 25 an elevator of great vertical reach.

The angle strips 17 extend above the platform and support horizontal front and back 30 angle strips 22 secured thereto. These strips have their ends turned outwardly at right angles to receive side guard strips 23 each of which is pivoted at one end to one of the strips 22 for arcuate movement, and is provided at its other end with a slot for reception 35 of a headed pin 24 secured in the end of the other strip 22. By raising the inner guard strip 23 the blocks of ice may be readily placed upon the elevator from within 40 the body of the truck, after which the inner strip is lowered, the ice being held upon the elevator during raising thereof by strips 23, as indicated in Fig. 1. When the elevator has been raised so as to bring the platform substantially flush with, or slightly above, the 45 roof of a refrigerator car at the side of which the truck is positioned, by raising the outer side strip 23 the ice may be readily removed and slid upon car roof so as to be 50 easily loaded into the car. By positioning the elevator at one side of the truck body it may be readily positioned adjacent the side 55 of a refrigerator car or similar structure by driving the truck alongside the car, after which the elevator may be used as stated. When in lowered position the elevator normally provides a closure for opening 2 of the body, while providing means whereby the ice may be readily removed from the forward end of the truck body across the elevator when desired.

When the loads to be lifted are relatively light, the modified construction shown in 60 Figs. 6 and 7 may be used to advantage and 65 at lower cost; in this design but one cylinder

and a bracket-shaped platform are used. The construction of the telescoping guides, piston and two to one rope suspension are substantially the same as already explained in the two cylinder construction, with the exception that the elevator platform will have to be secured firmly to the corresponding cable end and that the piston may perhaps be made larger to provide sufficient mechanical resistance to the loads which in this case 70 create greater strains upon the cylinder owing to the overhanging platform. A further advantage of this construction lies in the reduced floor space required owing to the elimination of one cylinder. In Figs. 6 and 7, the numbers refer to the similar parts of 75 same number shown in the two cylinder construction.

While I have illustrated and described herein the preferred embodiment of my invention, and one which I have found by actual use to be very practical, it may be found desirable after continued experience to make slight changes in construction and arrangement of the details as well as location upon a truck of my invention, and I intend to include in this application all such variations as fall within the scope of the appended claims.

What I claim is:

1. The combination with an automobile truck, of an elevator carried by the body at one side thereof and adapted to form a guard for the body when lowered, and means for operating said elevator.

2. The combination with a truck, of two spaced cylinders; an elevator operable between said cylinders; pistons operable in the cylinders; plungers connected to said pistons; sheaves carried by the plungers; a cable passed over said sheaves and movably guided beneath the elevator and having its ends fixed, and means for guiding said elevator during operation thereof.

3. The combination with a truck, of two spaced cylinders; an elevator operable between said cylinders; pistons operable in the cylinders; plungers connected to said pistons, sheaves carried by the plungers; a cable passed over said sheaves and beneath the elevator and having its ends fixed, and telescoping guide members secured to said cylinders and plungers and guiding the elevator during operation thereof, along and above said cylinders.

4. The combination with a truck including a body provided with an opening through one side, of an elevator adapted to normally close said opening when in lowered position and provided at its opposite sides with removable holding members for retaining articles upon the elevator.

5. The combination with a truck, of two spaced cylinders, an elevator operable between said cylinders; plungers connected to

said cylinders; sheaves carried by the plungers; a cable passed over said sheaves and beneath the elevator and having its ends fixed; a stationary guide secured to each cylinder; a movable guide rail secured to each plunger and running along said stationary guide, and guide shoes secured to the elevator.

6. The combination with a truck, of two spaced cylinders; an elevator operable between said cylinders; plungers connected to said cylinders; sheaves carried by the plungers; a cable passed over said sheaves and beneath said elevator and having its ends fixed; a stationary guide of channel shaped cross section secured to each cylinder; a movable guide-rail of T section secured to each plunger guided by and running within said stationary guide, and guide shoes secured to the elevator, guided by and running along the central web of said movable guide rails.

7. The combination with a truck, of two spaced cylinders; an elevator operable between said cylinders; plungers connected to said cylinders; sheaves carried by the plungers; a cable passed over said sheaves and beneath the elevator and having its ends fixed; a stationary guide secured to each cylinder; a movable guide rail secured to each plunger and running along said stationary guide; guide shoes secured to the elevator, said elevator occupying but a fractional part of the body-space of said truck.

8. In combination with a cylinder and piston elevator of two to one cable and sheave construction, means for reducing the

required overhead room for piston and guide, when in lowered position, to approximately one-half of the rise of the elevator platform; said means consisting of a stationary guide rail secured to the cylinder, a movable guide rail secured to the piston and running along said stationary guide and guide shoes or runners secured to the elevator.

9. In combination with a cylinder and piston elevator of two to one cable and sheave construction, a stationary guide rail secured to the cylinder; a movable guide rail secured to the piston and running along said stationary guide, and guide shoes or runners secured to the elevator.

10. In combination with a cylinder and piston elevator of two to one cable and sheave construction, a stationary guide rail of channel shaped cross section secured to the cylinder; a movable guide rail of T section secured to the piston, guided and running within said stationary guide and guide shoes secured to the elevator, guided by and running along the central web of said movable guide rail.

11. The combination with an automobile truck of a cylinder and piston elevator of two to one rope and sheave construction; a stationary guide rail secured to the cylinder; a movable guide rail secured to the piston and running along said stationary guide, and guide shoes or runners secured to the elevator, said elevator occupying but a fractional part of the body-space of said truck.

In testimony whereof I affix my signature.
JOHN H. STUBBE.
